WELL DRILL

Application filed August 23, 1927. Serial No. 214,964.

This invention has to do with a well drill and has particular reference to a drill or bit for use in drilling wells with the rotary method. It is a general object of this invention to provide an effective, efficient and improved device of this character.

It is a general object of this invention to provide a bit which operates to cut by stages, for instance, by making an initial cut to leave a core and then cutting away the core.

It is another object of this invention to provide a bit including two cooperating cutting means, one operable to make an annular cut, the other operable to cut away the center or core left by the one first mentioned means.

A further object of this invention is to provide a bit having a body of improved formation wherein an annular end part is supported through a plurality of spaced legs.

The various objects and features of the invention will be best and more fully understood from the following detailed description of a typical form and application of the invention throughout which description we will refer to the accompanying drawing in which

Fig. 1 is a side elevation of the bit, Fig. 2 is a transverse sectional view of the bit being a view taken as indicated by line 2-2 on Fig. 1. Fig. 3 is a detailed sectional view taken as indicated by line 3-3 on Fig. 2. Fig. 4 is a detailed sectional view taken as indicated by line 4-4 on Fig. 2 and Fig. 5 is a detailed sectional view taken as indicated by line 5-5 on Fig. 1.

The bit includes, generally, a body 10, outer cutter cutting means 11 carried by the body to make an annular cut in the formation being drilled, inner cutting means 12 carried by the body operable to remove or cut away the center or core left by the outer cutting means 11, and various other parts and features, the details of which will be hereinafter described.

The body 10 is provided at its upper end

with a central vertically disposed shank 13, at its lower end with an annular end part 14, and has a plurality of spaced legs 15 connecting the shank 13 to the annular end part 14. The shank 13 is provided at its upper end with a tapered screw threaded pin projection 16 whereby the bit can be attached to a string of drilling tools, for instance, a string of drill pipe.

The annular end part 14 of the bit is provided as a carrier or mounting for the outer cutting means 11. The outside diameter of the annular end part 14 is somewhat less than the diameter of the hole to be drilled and in practice the inside diameter is made as large as possible leaving the ring sufficiently thick to properly support the cutting means 11. Likewise the length or vertical dimension of the annular end part 14 is made such as to give this part the proper body and strength to withstand the strains to which it is subjected.

The legs 15 provided to connect the shank 13 and the annular end part 14 may vary in number, arrangement and proportions. In practice, the bit may be provided with two legs 15 spaced 180 degrees apart and proportioned substantially as shown throughout the drawing. The annular end part 14 is larger in diameter than the shank 13 and, therefore, the legs 15 extend outwardly and downwardly from the lower end of the shank 13 to join the upper end of the end part 14. In practice, the various parts of the body, for instance, the shank 13, legs 15 and part 14, may be forged or otherwise formed integrally or they may be formed separately and suitably joined or connected. In the drawing we have shown the legs 15 integral with the shank 13 and have shown the annular end part 14 attached to the lower ends of the legs 15. In this particular case, the lower ends 16 of the legs extend into recesses 17 provided in the end part 14 and in practice the joining parts of the legs and end part 14 are welded to-

gether to make a solid connection in which the parts are practically integral.

The outer cutting means 11 carried by the annular end part 14 of the body may, as far as the broader principles of the invention are concerned, be of any type or formation operable to make an annular cut in the formation being drilled. In the drawing we have shown the means 11 as comprising a plurality of blade cutters carried by the annular end part 14 to project from the lower end. In the arrangement shown the means 11 includes a plurality of outwardly projecting cutters 18 and plurality of inwardly projecting cutters 19. The cutters 18 are carried by the annular end part 14 to project downwardly from or ahead of it and also radially outward from it. Thus, the cutters 18 cut ahead of the annular end 14 of the body and cut outward clearance for it. In the drawing we have shown four cutters 18 carried by the annular end part 14, each cutter being provided with a sharpened lower edge 20 and a sharpened outer side edge 21. The cutters 18 seat in upwardly converging sockets 22 provided in the lower end of the part 14 and have upwardly extending shanks 23 that project upwardly through vertical openings 24 in the part 14 to project above the part 14.

Retaining nuts 25 are screw threaded to the upper ends of the shanks 23 to hold the cutters tightly in place. The cutters 19 of the means 11 may be similar generally to the cutters 18 except that they project inward radially from the end part 14 instead of outwardly. The cutters 19 project downwardly from the lower end of the annular end part 14 and are provided with lower cutting edges 26 and inner side cutting edges 27. We have shown two cutters 19 arranged 180 degrees apart. Further, in the arrangement shown in the drawing, the cutters 19 are shorter than the cutters 18 and, therefore, do not project downwardly from the lower end of the part 14 as far as the cutters 18. The cutters 19 may be mounted and retained in part 14 in the same manner as are the cutters 18. The cutting means 11 just described, being carried by the annular lower end part 14 of the body, operates to make an annular cut in the formation being drilled, that is in the bottom of the hole being drilled, leaving a center or core that passes upwardly through the part 14 as the bit advances.

The inner cutting means 12 is provided by our invention to remove the core left standing by the outer cutting means 11. In the form of the invention illustrated in the drawing the inner cutting means 12 includes two blade cutters 30 mounted on the inner sides of the legs 15. The blades 30 are carried by the legs 15 so that they are diametrically opposite each other and extend upwardly and inwardly to be in an inverted V formation. The blades 30 shown in the drawing

have their inner or cutting edges stepped so that each blade presents a plurality of inwardly faced vertically disposed cutting edges 32 and a plurality of downwardly facing horizontally disposed cutting edges 33. Further in the preferred arrangement the two blades 30 are stepped, as just described, so that opposite or corresponding vertical cutting edges 32 are different distances from the vertical center of the tool while the horizontal cutting edges of the two blades occur at different points vertically of the tool. With this formation of cutters 30, which is clearly shown in Fig. 1 of the drawing, the top or upper end of the core as it passes upwardly in the bit is cut or trimmed away. It is to be noted that the spaces between the legs 15 leave ample room or clearance for the discharge of cuttings made by the blades 30. In the construction illustrated in the drawing blade holders 40 are secured to the inner sides of the legs 15. The inner parts of the blades are recessed into the holders and suitable bolts 41 are provided to retain the blades in the holders. It will be obvious, however, that any suitable construction may be employed in mounting the blades in the proper manner between the legs 15.

In accordance with our invention provision is made for directing circulation fluid, for instance mud laden fluid, to the cutting parts to keep the cuttings washed away and to prevent the undesirable accumulation of mud or cuttings on the various parts of the tool. In the construction illustrated in the drawing the fluid passage 50 extends downwardly through the pin 16 and shank 13 to conduct circulating fluid from the string of drill pipe carrying the bit to distributing conduits or pipes 51 and 52. The distributing pipes 51 conduct the circulating fluid from the openings 50 to openings 54 in the annular lower end part 14. The openings 54 discharged downwardly immediately ahead of the cutters of the means 11, keeping the cutters clean and keeping the hole properly flushed during operation of the bit. Pipes 51 may in practice be arranged adjacent the legs 15 so that they are held and protected by the legs. The pipe or pipes 52 receive circulating fluid from the opening 50 and direct it downwardly at the upper ends of the blades 30 to flush the blades during the operation of the bit.

From the foregoing description of the structural features of the bit it is believed that its action or mode of operation will be readily understood. However, we wish to particularly point out a few of the salient features which are peculiar to our invention.

The bit when in operation makes a comparatively narrow annular cut into the formation or into the bottom of the hole being drilled leaving a comparatively large core to extend upwardly into the bit to be destroyed or re-

moved by the secondary or inner cutting means. It is well recognized that it is far more difficult to make a cut directly into a solid or completely confined body, for instance, directly into the bottom of a hole, than it is to cut away unconfined material, for instance, a projection of material having free or unsupported parts. With our bit, a minimum amount of cutting or drilling is done into solid formation. The outer cutting means 11 make this initial cut into the solid formation. However, because of the fact that the cut made is comparatively narrow, the cutting edges are comparatively short and even though dulled are effective in penetrating or entering the formation. The inner cutting means 12 operates on the unconfined formation, that is, upon the core which stands in the bottom of the hole or projects into the bit. This core, because of the manner in which it projects upwardly from the bottom of the hole, has no side support and is, therefore, easily removed or drilled away by the means 12. Further, the ample clearance around the core at or opposite the cutting means 12 allows the core to freely break down or be cut away.

The bit provided by our invention has another noteworthy feature distinguishing it from other drilling tools, that is, it tends to maintain or to drill a straight hole. An ordinary pilot or central cutting bit, upon engaging or drilling into a hard inclined formation, is deflected more or less by the formation with the result that the hole drilled is crooked or out of line. With our bit the annular or outer cutting means 11, being of comparatively large diameter and in making a comparatively narrow cut, enters or drills into and through an inclined formation with little or no tendency to become deflected. Further, the cutting means 12 in acting on the core has little or no influence on the direction of feed of the bit as the core cuts away with comparatively little resistance. Further in this connection, the annular end part 14 of the body, in surrounding the core left by the outer cutting means 11, is held or guided more or less by the core, thus further tending to maintain the bit central or straight.

Having described only a typical preferred form of our invention we do not wish to limit ourselves to the specific details set forth, but wish to reserve to ourselves any changes or variations that may appear to those skilled in the art or fall within the scope of the following claim.

Having described our invention, we claim:

A well drilling bit having a shank, downwardly projecting spaced leg members depending from said shank, an annular member projecting from the lower end of said leg members, core cutters on the lower end of said annular member, secondary cutters located within said leg members and arranged in V-

formation for the purpose of destroying the core cut by said first mentioned cutters, each of said secondary cutters comprising a flat plate having a series of stepped cutter portions on one edge thereof and means for attaching said secondary cutters to said leg members.

In witness that we claim the foregoing we have hereunto subscribed our names this 15th day of August, 1927.
